(57) **CLAIM**

The ornamental design for a hair bonnet, as shown and described.

DESCRIPTION

FIG. 1 is a front perspective view of a hair bonnet according to my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of the hair bonnet of FIG. 1 with the two ties in an untied configuration; and,

FIG. 9 is a bottom view of the hair bonnet of FIG. 8.

The broken lines in FIGS. 8 and 9 depict a symbolic break along the length of the tie features of the hair bonnet and form no part of the claimed design. The appearance of any portion of the article between the symbolic break lines forms no part of the claimed design.
